SOOT CLEANER FOR AIR PREHEATERS

Fred C. Arey, Oak Park, Ill., assignor, by mesne assignments, to Vulcan Soot Blower Corporation, Du Bois, Pa., a corporation of Pennsylvania

Application March 2, 1931. Serial No. 519,527

9 Claims. (Cl. 257—1)

Sometimes the combustion gases from furnaces are passed through heat interchangers whereby some of the heat of these gases is transferred to the air entering the furnace as 5 air of combustion; thus recovering some of the heat that would otherwise escape through the stack. These air preheaters usually contain a great many vertical tubes through which the combustion gases pass and around which the 10 air to be heated flows. Soot collects in these tubes or flues, and, unless it is removed, reduces the efficiency of the heat interchanger. It is, therefore, the practice to blow the soot out of these tubes or flues from time to time. Because 15 there are so many of these tubes, only a few at a time are blown; the tubes being disposed in parallel rows, and headers having thereon discharge nozzles extending parallel to and being moved from one row to another, so as to blow 20 entire rows successively. So far as I am aware, these blowing headers have heretofore been manipulated manually, the labor involved being considerable, and great care being required to insure that the blowing nozzles will be properly 25 registered with the tubes that are being blown.

The object of the present invention is to produce a simple and novel mechanism or apparatus whereby the headers may be moved by power means which shall shift the headers quickly 30 and position them accurately.

Where there are many rows of tubes to be blown, it is customary to employ two headers arranged parallel to each other and at a distance apart equal to one-half the distance between the two endmost rows, so that one-half 35 of the tubes will be blown by one header and the remaining half by the other header. One of the objects of the present invention is to produce a simple and novel power apparatus or 40 mechanism for operating such double headers.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a plan view of an apparatus arranged in accordance with my invention, applied to a heat interchanger of which fragments are shown; Fig. 2 is a section on line 2—2 of Fig. 1; Fig. 3 is a longitudinal section through the operating cylinder or engine, the piping thereto and the manual control valve being also

shown; Fig. 4 is a section on an enlarged scale on line 4—4 of Fig. 1; Fig. 5 is a side view of the engine; Fig. 6 is a section on line 6—6 of Fig. 5; Fig. 7 is a section on line 7—7 of Fig. 4; Figs. 8 and 9 are sections, on a larger scale, taken on lines 8—8 and 9—9, respectively, of Fig. 6; and Figs. 10 and 11 are views similar to Fig. 9, showing different positions of the parts, and a fragment of the ratchet wheel being shown in dotted lines instead of in full lines.

Referring to Figs. 1 and 2 of the drawings, A represents the casing or housing of a heat interchanger filled with numerous parallel rows of tubes or flues B of which only a few are shown. In the particular arrangement shown, the tubes in adjacent rows are staggered so as to permit a partial nesting of the tubes and an efficient utilization of the space within the casing or housing. The lower ends of the tubes or flues are open and are located at some distance above the bottom of the casing, so as to provide, below the tubes, a space or chamber in which the blowing headers may be disposed. There are two headers, 1 and 2, each as long as one of the rows, and each provided with two sets of nozzles 3 and 4, so placed that each header will blow two rows of tubes or flues at a time. The header 1 is fixed upon the end of a large tubular member or pipe 5. The header 2 is fixed upon the end of a tubular member or pipe 6, considerably smaller in diameter than the member 5 and extending through and fixed to the latter so that the two pipes act as a single member or unit. The pipe 6 projects from the header end of the pipe 5 a distance equal to one-half the length of the heat interchanger so that, when either header is registering with two extreme rows of flues, the other header is registering with two rows along the middle of the heat interchanger. Steam, air, or other fluid under pressure is delivered into the outer end of the pipe 5 from a supply pipe 7 through a flexible connection 8. In the same way, blowing fluids may be supplied to the outer end of the pipe 6 which projects beyond the pipe 5, from a supply pipe 9 through a suitable flexible connection 10. The supply pipes 7 and 9 are provided with manual controlling valves 11 and 12, respectively.

When the valve 11 is opened, blowing fluids will be supplied to the header 1, so that, if the headers are moved inwardly from the position shown in Fig. 1, step by step, one-half of the flues may be blown, two rows at a time, by the header 1. When the header 1 reaches the middle of the heat interchanger, the other

header will be at the rear end, so that, if the valve 11 is closed and the valve 12 opened, the rear header will become the active one; by moving the headers forward again, step by step, 5 the rear half of the flues will be blown, two rows at a time.

The headers may be provided at their ends with wheels 13 running on suitable stationary tracks 14 which, therefore, support the weight 10 of the headers.

The pipes 5 and 6 may be held in fixed telescoped relation to each other in any suitable manner. Thus, the pipe 5 may be made sectional and have therein a suitable coupling, such 15 as indicated at 15, Fig. 7; one member of the coupling having an internal spider 16 provided with a central hub or sleeve 17 into which meeting sections of the inner pipe 6 may be screwed. This particular coupling is placed close to the 20 header 1. At the forward or outer end of the pipe 5 there is a suitable head 18 closing the pipe 5 and centering the pipe 6 therein.

In order to move the headers back and forth through the heat interchanger, I provide the 25 pipe 5 with rack teeth 20 distributed from one end thereof to the other so as to transform the pipe into a rack bar, and also provide power mechanism to cooperate with the rack bar. In the arrangement shown, the motor or engine 30 comprises a vertical cylinder 22 containing a reciprocable piston 23 having a rod 24 extending down through the bottom end of the cylinder. The piston rod is connected to the upper head of a vertical rack bar 25 meshing with a toothed 35 segment 26 loose on a transverse shaft 27 underlying the pipe 5 adjacent to the heat interchanger. Fixed to the shaft 27 is a ratchet wheel 28 having four teeth 29. On the toothed segment is a pawl 30 cooperating with the 40 ratchet wheel. The parts are so proportioned that, during a stroke of the piston in one direction, it will cause the pawl to drive the ratchet wheel through a quarter turn. The pawl is double-ended, so that it may be utilized to turn 45 the ratchet wheel, step by step, in either direction. In the arrangement shown, as best illustrated in Fig. 8, there is a tension spring 31, connected at one end to the pawl and at the other end to the toothed segment; the points of 50 connection of the spring being so disposed in relation to the axis 32, about which the pawl swings, that the spring will serve to hold down either end of the pawl. Two cords 33 and 34 are connected to the pawl. When one end of 55 the pawl is in operative relation to the ratchet wheel, a pull on the corresponding cord will move that end of the pawl into an idle position and the other end into its working position. On the shaft 27, and rotatable therewith, 60 is a pinion 35 that meshes with the rack teeth 20 on the blower pipe. Therefore, during one stroke of each cycle of the engine, the headers will be moved a distance corresponding to a quarter turn of the pinion. The parts are so 65 proportioned that this distance is just equal to twice the space between successive rows of flues in the heat interchanger; whereby the headers will be moved back or forward, two rows at a time, during each cycle of the engine. In other 70 words, when the pawl is in one of its working positions, and the engine is operated, the headers will be moved backward, whereas, when the pawl is shifted, as heretofore explained, the headers will be moved forward, step by step.

75 In setting up the apparatus, the headers are

placed accurately under the rows of flues beneath which they are to lie at one end of their stroke. Then, since the rows of flues are accurately spaced, the nozzles on the headers will always register with the proper rows of flues when the headers come to rest between successive steps in their movements. 80

To facilitate the initial setting of the headers, I do not mount the pinion 35 directly on the shaft 27, but support it on a sleeve 37 that is fixed to the shaft; the pinion being rotatable on the sleeve. The sleeve has thereon two separated radial lugs 38 and 39, and the pinion 35 has a finger or pin 40 extending between these lugs. There is a set screw 41 passing through each lug into engagement with the projection or finger 40. By adjusting the set screws 41, the pinion may be shifted slightly angularly of the shaft so as to make a final fine adjustment 90 to bring the nozzles on the headers into exact 95 registration with the flues.

It is essential, in order to insure accurate registration of the nozzles with the flues, that the ratchet wheel be brought to rest at the end of the working stroke of the engine and does not 100 overrun more or less. To this end I have provided novel stop means that positively stops the ratchet wheel whenever it has made a quarter turn. This feature is best shown in Figs. 9, 10 and 11. On a stationary part 43 of the casting 105 44, that supports the engine and the operating mechanism, is mounted a double-ended pawl 45 lying in the plane of the ratchet wheel. Hung on the same shaft 46 that supports the pawl 45 is a dog 47 lying in the plane of a hub 48 on 110 one side of the toothed segment. The dog has a roller 49 that rides on the periphery of this hub, and it carries two compression springs 50 and 51 seated in pockets in the dog. The outer ends of the compression springs are adapted to 115 underly lugs 52 and 53 on opposite ends of the pawl 45. In the periphery of the hub 48 is a notch 54 into which the roller on the dog may drop when the notch and the roller register. The parts are so proportioned that, when the 120 roller is out of the notch and resting on the periphery of the hub, one of the springs 50 and 51 will be compressed, whereas the other spring will be in its normal expanded condition. With the parts in the positions shown in Fig. 9, a 125 downward movement of the rack bar 25 will cause the pawl 30 to turn the ratchet wheel in a counter-clockwise direction. The end 45a of the pawl 45 stands clear of the tooth that must pass this pawl, and the notch 54 is at some dis- 130 tance from the roller on the holding dog. As the ratchet wheel and the toothed segment continue to turn, the notch will approach the dog and the roller on the dog will drop into the same, as indicated in Fig. 10. The spring 51, 135 which was originally under compression, and has, therefore, held the nose 45a of the holding pawl up, expands as the dog drops into the notch and the spring 50, which originally stood away from the lug 52, is brought into engagement with 140 this lug, so that the holding pawl becomes balanced on these springs, and both ends stand clear of the ratchet wheel. Then, during the further movement of the toothed segment and ratchet wheel, the notch passes out from under 145 the dog, causing the dog to be swung into the position shown in Fig. 11, releasing the spring 51 and compressing the spring 50. The spring 50, therefore, rocks the holding pawl in the direction to bring the nose 45a of the holding pawl 150

down into the path of the teeth on the ratchet wheel. This action occurs before the end of the stroke of the engine and, therefore, before the ratchet wheel has completed its intended movement, so that, when the ratchet wheel has made a quarter of a turn, the holding pawl will lie in the path of a tooth, and will, therefore, prevent overrunning of the ratchet wheel. During the return stroke of the rack 25 and the toothed segment, the actions just described are performed in reverse order; the notch moving in the clockwise direction in Fig. 11 to the position shown in Fig. 10, causing the holding pawl to assume a neutral position; and, finally, the positions shown in Fig. 9 being reached, and the holding pawl being so placed that the ratchet wheel may be turned upon the next working stroke of the operating pawl.

It will be seen that the holding pawl is effective to stop the ratchet wheel, regardless of the direction in which the ratchet wheel is turning because, assuming that the operating pawl 30 is reversed in Fig. 9, the down stroke of the rack 25 will be an idle stroke during which the movement of the toothed segment will bring the holding pawl into the position shown in Fig. 11. Consequently, on the up stroke of the rack, the ratchet wheel will turn in the clockwise direction without being interfered with by the holding pawl until, toward the end of the stroke, the holding pawl has been brought into the position shown in Fig. 9, and, therefore, serves to arrest further clockwise movement of the ratchet wheel until after the next down stroke of the rack.

It will, therefore, be seen that, after having opened the supply valve 11, the operator need only cause the engine piston to reciprocate, in order to move the headers and cause the forward half of the flues to be blown; and then, after shutting the valve 11 and opening the valve 12, and reversing the actuating pawl 30, set the engine in motion again so as to move the headers forward and blow the rear half of the flues.

The engine may be controlled in any suitable way. In the arrangement shown, as will best be seen from Fig. 3, there is a steam supply pipe 56 adapted to deliver steam into opposite ends of the cylinder through pipes 57 and 58. Between the main and branch pipes is a four-way valve 59 adapted to connect either of the pipes 57 or 58 to the pipe 56 or to an outlet 60 to atmosphere.

The engine itself contains some novel features. The main ports 61 and 62, leading from the pipes 57 and 58, respectively, to the interior of the cylinder, are at some distance from the ends of the cylinder so that each will be covered by the piston when the latter is in the corresponding end of the cylinder. Each port is connected to the extreme end of the cylinder by means of a passage 63 containing a spring-held check valve 64 that opens inwardly toward the cylinder. Therefore, when, for example, the piston is up, as shown in Fig. 3, and air or steam is admitted to pipe 57, it flows in the port 61 and from there past the check valve into the upper end of the cylinder. The passage 63 is restricted, so that the motive fluid entering the cylinder through the same will move the piston slowly until the upper edge of the piston passes the main supply port 61; whereupon the piston moves rapidly on its downward stroke until the lower edge covers the port 62 which has been

acting as the exhaust port. When the port 62 is covered, the fluid beneath the piston is confined and forms a cushion to check the downward movement of the piston. I have, however, provided each end of the cylinder with a small by-passage 65 extending around the check valve so that the air or steam pocketed between the piston and the adjacent cylinder head may escape very slowly through this small by-passage. In other words, the piston is not suddenly stopped, nor is the pocketed fluid confined further than to compel it to leak out slowly and thus permit the piston to come gradually to a position of rest. By this arrangement, I am able to produce a rapid movement of the piston during the time the blowing nozzles are out of registration with the flues, during the shifting of the headers, and thus avoid loss of the blowing medium; the slow movement at the beginning of the stroke, and again at the end, occurring while the nozzles are still blowing into the flues.

Since the nozzles are ordinarily permitted to blow into the same flues for ten or twelve seconds, ample time is given the operator to cause the piston a make its return stroke before another working stroke is needed to advance the headers through the next step.

It will thus be seen that I have produced a simple and rugged mechanism whereby a progressive blowing of a large number of flues may be carried out efficiently and expeditiously, without requiring any further care or attention of the operator than to open and close the controlling valves (when the valves are all controlled manually as shown), and shift the operating pawl when one half of the flues have been blown. It will also be seen that I have produced a simple and novel stop to prevent overrunning of a ratchet wheel that may be turned step by step in either direction; together with a simple and novel reciprocating engine in which the piston is effectively combined, and in which rapid acceleration at the beginning of each stroke and deceleration at the end of each stroke is rapid, so that high speed in operation is secured.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. The combination with tubes arranged in parallel, equally-spaced rows, a blowing header device parallel to said rows and movable past the ends of the tubes, a pipe for supplying fluid under pressure to such header, of a reciprocating engine, and driving connections between said pipe and said engine to cause said header to move from one row to another during one stroke of the engine and to remain stationary during the other stroke.

2. The combination with tubes arranged in parallel, equally-spaced rows, a blowing header device parallel to said rows and movable past the ends of the tubes, a pipe for supplying fluid under pressure to such header, of a reciprocating engine, and positive driving connections between said engine and said pipe to cause said header device to move through a distance equal to that between two rows of tubes to be blown during each cycle of engine operation.

3. The combination with tubes arranged in par-

- allel, equally-spaced rows, and two blowing headers in fixed relation to each other at a distance apart equal to the total spacing between one half of the rows, the headers being parallel to said rows and movable transversely of the latter, of means to move said headers step by step from one row to another through a distance equal to the spacing between one half of said rows and then back to the starting point, 10 means to arrest the headers in registration with rows of tubes at the end of each step, and means to admit fluid under pressure into either header whereby one-half of the rows of tubes may be blown while the headers are moved step by step in one direction and the other half be blown while the headers are moved step by step in the opposite direction.
4. In an apparatus of the character described, two blowing headers spaced apart from and in parallel relation to each other, a pipe fixed to one of the headers, and a second pipe extending through the first pipe and past the header connected to that pipe to the other header.
5. In an apparatus of the character described, two blowing headers spaced apart from and in parallel relation to each other, a pipe fixed to one of the headers, a second pipe extending through the first pipe and past the header connected to that pipe to the other header, the first-mentioned pipe having a row of rack teeth extending along the same on the outside thereof, a pinion engaged with said rack teeth, and means to turn said pinion step by step.
6. A soot blower comprising a blowing header, a rack fixed thereto and projecting therefrom, a pinion meshing with the rack, a ratchet wheel fixed to the pinion, a pawl cooperating with the ratchet wheel, the pawl being reversible and the teeth on the ratchet wheel being shaped to permit the wheel to be turned in either direction by the pawl, a reciprocable power device, and

driving connections between the power device and the pawl.

7. In combination, a soot blower comprising a header, a rack fixed thereto and projecting therefrom, a pinion meshing with the rack, a ratchet wheel fixed to said pinion, an operating pawl, a holding pawl, an actuator for the operating pawl, and means controlled by said actuator to maintain the holding pawl in an idle position at the beginning of a working stroke of the operating pawl and thereafter carry it into a position to stop the ratchet wheel at the end of the working stroke of the operating pawl.

8. In combination, a soot blower comprising a header, a rack fixed thereto and projecting therefrom, a pinion meshing with the rack, a ratchet wheel fixed to said pinion, a double-ended holding pawl mounted adjacent to said wheel and adapted in one working position to serve as a stop to limit rotation of the ratchet wheel in one direction and in its other position to limit rotation of the wheel in the opposite direction, a double-ended operating pawl, an actuator for the operating pawl, and means controlled by the actuator to 95 shift the holding pawl to cause it to prevent overrunning of the ratchet wheel when moved step by step in either direction by the operating pawl.

9. A soot blower comprising a blowing header, a rack fixed thereto and projecting therefrom, a pinion meshing with said rack, a power cylinder, a piston in said cylinder, means for admitting to the cylinder and controlling motive fluids to cause the piston to move very slowly at the beginning and end of each stroke and 110 rapidly during the remainder of the stroke, and means controlled by said piston to turn said pinion step by step.
